(57) CLAIM

The ornamental design for a label, as shown and described.

DESCRIPTION

The patent or application file contains at least one drawing executed in color. Copies of this patent or patent application publication with color drawing(s) will be provided by the Office upon request and payment of the necessary fee. The sole FIGURE is a top view of a label showing my new design.

The rear view of this design is unornamented and therefore not illustrated.

1 Claim, 1 Drawing Sheet
